UNITED STATES PATENT OFFICE

OTTO E. TRAUTMANN, OF ROCHESTER, NEW YORK, ASSIGNOR TO BAUSCH & LOMB
OPTICAL COMPANY, OF ROCHESTER, NEW YORK, A CORPORATION OF NEW YORK

DESIGN FOR AN OPERA-GLASS SUPPORT

Application filed August 1, 1929. Serial No. 32,258. Term of patent 7 years.

To all whom it may concern:

Be it known that I, OTTO E. TRAUTMANN, a citizen of the United States, and a resident of Rochester, county of Monroe and State of New York, have invented a new, original, and ornamental Design for Opera-Glass Support, of which the following is a specification, reference being had to the accompanying drawing, forming a part hereof.

Fig. 1 is a front elevation of an opera glass support, showing my new design.

Fig. 2 is a side view thereof.

Fig. 3 is a top plan view of same.

I claim:

The ornamental design for an opera glass support substantially as shown.

OTTO E. TRAUTMANN.
